UNITED STATES PATENT OFFICE.

MALCOLM TIEPKE WATERMAN, OF CEDAR RAPIDS, IOWA.

TOWING DEVICE.

1,390,942.

Specification of Letters Patent. Patented Sept. 13, 1921.

Application filed July 8, 1920. Serial No. 394,624.

To all whom it may concern:

Be it known that I, MALCOLM T. WATERMAN, a citizen of the United States, and a resident of Cedar Rapids, in the county of 5 Linn and State of Iowa, have invented a new and Improved Towing Device, of which the following is a full, clear, and exact description.

This invention relates to improvements 10 in towing devices, and more particularly to an improved coupling means for connecting a pair of motorcycles of the side car type, so that a stalled motor car can be readily towed.

15 A further object is to provide a device of the character stated which can be utilized without injury to either of the motorcycles, which can be conveniently carried from place to place, and which will maintain the 20 motorcycles spaced a relative distance apart and efficiently perform its functions whether going up grade or down.

With these and other objects in view the invention consists in certain novel features 25 of construction, and combinations and arrangements of parts as will be more fully hereinafter described and pointed out in the claims.

30 In the accompanying drawings— Figure 1 is a top plan view illustrating my improved device in operative position.

Fig. 2 is an enlarged view in side elevation showing fragments of the connected motorcycles.

35 Fig. 3 is a perspective view of the device detached.

1 and 2 represent a pair of motorcycles of the side car type and for purposes of illustrating my invention, the rear car 2 40 may be supposed to have stalled and it is necessary to tow the same into the garage or place of repair although it is, of course, obvious that my improved device might be utilized to connect motorcycles so that only 45 the power or engine of one may be utilized for moving both motorcycles.

My improved towing device comprises a pair of bars 3, 3, which may be of any desired length and connected at one end by a 50 metal strap 4 forming a coupling eye 5 adapted to be attached by a rope or other means 6 to the stand 7 of the towing motorcycle.

The inner faces of the bars 3 at their 55 forward ends are beveled or inclined, as

shown at 8, so that the strap 4 serves to hold the bars 3 at an angle to each other as shown clearly in Figs. 1 and 3. The bars 3, 3, are provided at their rear ends against their inner faces with clamping blocks 9 connected to the bars 3 by bolts 10 and wing nuts 11. These blocks 9 and the inner faces of the bars 3 are preferably provided with cushioning sheets 12 which are preferably of rubber or other similar material and said blocks and their cushioning sheets are preferably provided with registering recesses 13 so as to form a gripping or clamping engagement with the mudguard brace rods 14 of the motorcycle to be towed. 70

In operation, the clamping blocks 9 are removed and located against the inner faces of the mudguard braces 14 with the latter in the recesses 13 and then the bolts 10 are tightened by means of the nuts 11 to securely clamp the bars 3, 3, to the motorcycle to be towed. The forward end of the towing device is connected by the rope or other flexible connecting means 6 with the stand 7 which is ordinarily provided at the 80 rear of motorcycles, the rope being passed through said stand and through the eye 5 of the metal strap 4 so that when the front motorcycle 1 is operated, the rear motorcycle 2 will be effectually towed. 85

Various slight changes might be made in the general form and arrangement of parts described without departing from the invention, and hence I do not limit myself to the precise details set forth, but consider myself at liberty to make such changes and alterations as fairly fall within the spirit and scope of the appended claims. 90

I claim:

1. A towing device of the character described, comprising a pair of bars located at an angle to each other, a strap connecting said bars at one end and having an eye therein, cushioned blocks secured to the inner faces of the bars at their free ends, and bolts projecting through the blocks and bars and securing the parts together. 95

2. A towing device, comprising a pair of bars located at an angle to each other, clamping blocks on the inner faces of said 105 bars at one end, cushioning sheets secured to said blocks and to the inner faces of the bars, bolts projecting through the blocks and bars, and nuts on the ends of the bolts.

MALCOLM TIEPKE WATERMAN.
